UNITED STATES PATENT OFFICE.

WINFIELD SCOTT PROSKEY, OF OCALA, FLORIDA, ASSIGNOR OF ONE-HALF
TO DAVID PROSKEY, OF PATERSON, NEW JERSEY.

HYDROCARBON INCANDESCENT LAMP.

SPECIFICATION forming part of Letters Patent No. 628,415, dated July 4, 1899.

Application filed May 19, 1899. Serial No. 717,479. (No model.)

To all whom it may concern:

Be it known that I, WINFIELD SCOTT PROSKEY, a citizen of the United States, residing at Ocala, Marion county, State of Florida, have 5 invented certain new and useful Improvements in Hydrocarbon Incandescent Lamps, of which the following is a specification.

This invention relates to hydrocarbon-vapor lamps for incandescent lighting, the objects of the invention being to provide an improved construction of parts and to produce an improved lamp; and the invention consists in the various features of construction and arrangement of parts having the general 15 mode of operation substantially as hereinafter more particularly set forth.

Referring to the accompanying drawings, Figure 1 is a longitudinal vertical section of a lamp, showing the preferred embodiment of my invention. Fig. 2 is an enlarged section showing more particularly the vaporizer and its attachments. Fig. 3 is a plan view of the preferred form of vaporizer and gas-burner for heating the same. Fig. 4 is an enlarged 25 detail view of the nozzle, and Fig. 5 is a side view representing a conventional source of supply for the fuel or hydrocarbon for the lamp and the gas for the gas-burner.

One of the principal objects of my present 30 invention is to provide an improved means for the production of the initial vaporization of the hydrocarbon or fuel used to produce the incandescence of the illuminating material, and to accomplish this, generally stated, my invention consists in arranging in close 35 proximity to the vaporizer an acetylene-gas burner adapted to produce a blue or Bunsen flame which shall impinge directly upon the vaporizer and quickly heat the same to a temperature sufficient to vaporize the fuel or hydrocarbon, and this gas-burner is connected 40 to a suitable source of acetylene-gas supply and an acetylene-gas generator.

Another object of my invention is to provide 45 a practicable single-burner lamp of this general class and one which will be simple in construction and effective in operation, and this I accomplish by combining the features of invention as hereinafter set forth.

50 Another object is to provide an improved valve for the vapor, which shall not be liable to be clogged by deposits of carbon or other-

wise and which can be readily cleaned and which shall avoid the so-called "hissing" noise usually accompanying lamps of this 55 character.

Other features will appear from the detailed description of the invention as embodied in the construction shown in the drawings.

I may say that some of the features of the 60 lamp shown and about to be described are embodied in my prior application, Serial No. 699,865, filed December 20, 1898, and consequently are not claimed herein except in combination with other novel features. 65

In the drawings there is shown a single vaporizer in the form of a vaporization-coil A, adapted to be connected with a source of supply of the fuel or hydrocarbon, shown in the present instance as a tank T, the vaporizer 70 being connected therewith by a pipe T', having preferably suitable cut-off valves t t', the tank in the present instance being provided with means, such as a pump T², for putting the fuel under pressure and being shown detached, it being adapted to be located in any suitable and desirable position. The vaporization-coil A is shown as coiled around an air-intake tube B and as having a portion A' entering said tube and extending across the 80 same. In the present instance this portion is shown as a straight tube connected to the end of the coil proper and secured in any suitable way in the air-intake tube and preferably having an extension A² beyond the coil, 85 closed by a suitable plug A³, by means of which access can be obtained to this portion for the purpose of cleaning and otherwise.

As is well known, some means must be provided for producing initial vaporization of the 90 hydrocarbon and much time and ingenuity have been spent in providing a satisfactory means for heating the vaporizer so that when the fuel or hydrocarbon is supplied thereto it will immediately become vaporized, and I provide a construction adapted to use acetylene gas which I have found exceedingly effective and practicable. To accomplish this, I provide an acetylene-gas burner C, which is also shown in the form of a coil surrounding the 100 air-intake tube B and arranged in close proximity to the vaporization-coil A, so that the flame projecting upwardly and outwardly from the openings in the burner will impinge

directly upon the vaporization-coil. This acetylene-gas burner C is connected to a pipe C', which communicates directly with an acetylene-gas reservoir R, which in turn is shown as connected directly to an acetylene-gas generator R', which in the present instance is arranged in juxtaposition with the tank T. Interposed in this pipe C' is a jet c for the acetylene gas, and on the pipe is an adjustable sleeve 10 c', having openings corresponding with similar openings in the pipe to admit air, which, in connection with the acetylene gas, produces a blue or Bunsen flame at the burner C. This pipe is provided with suitable valves c² c³ for regulating the flow of the acetylene gas, and the pipe and burner may be supported in any suitable manner, as by the hood of the lamp (when it is used) or by loops or brackets c⁴.

I have found by actual practice that with 20 the use of acetylene gas in a burner arranged as above set forth the vaporization-coil can be heated in a very few seconds and at an exceedingly small cost for a great number of times and that the lamp may be set in operation 25 in a very short time.

Connected to the air-intake tube B is a mixing-chamber tube D, and this is shown as projecting up and through a head B' of the air-intake tube B, forming a chamber B² between 30 the tubes for the purpose of protecting and keeping relatively cool the nozzle of the vaporization-coil hereinafter described. The other end of the mixing-chamber tube D projects into the mixing-chamber E, which may be of 35 any desired shape or construction and which serves to thoroughly mix the vapor of the hydrocarbon and the air before they pass to the burner. In the present instance the mixing-chamber is closed by a screw-plug E', and connected to this plug E' is a ring E², adapted 40 to limit the movement of the valve in a manner hereinafter described.

Connected to the mixing-chamber is a burner F, in the present instance provided with a series 45 of openings f, through which the gas is projected. Mounted in proper relation to this burner is an incandescent, and while its form and arrangement may vary I have shown it in the form of a mantle G, suitably supported 50 as at G', so that the flame of the jets from the burner F will impinge upon the mantle and produce the desired incandescence and consequent illumination.

It is well known that one fruitful source of 55 trouble in this class of lamps is the nozzle through which the vapor of the fuel or hydrocarbon is forced, as it is liable to become clogged, and an unpleasant hissing sound is produced, and in order to avoid these difficulties I provide an improved nozzle H, attached 60 to the portion A' of the vaporizer. In the present instance formed on the portion A' is a hollow projection h, into which is screwed a detachable vapor-vent nozzle or plug H', having a conical central portion h', provided 65 with an opening h², through which the vapor passes, and this opening is controlled by a

needle i, mounted on a valve-stem l, which in the present instance extends through the mixing-chamber tube D, through the plug E' 70 of the mixing-chamber, and through the ring E², where it is provided with set-nuts i' i², and the end is provided with any suitable means for operating, as the thumb-piece l'. It will be seen that with this construction if there be 75 any tendency to deposit carbon on the interior of the nozzle it will naturally gravitate into the recessed portion H², surrounding the conical portion h' of the plug, and can be removed by removing the plug, and the needle i can be 80 manipulated by the valve-stem not only to regulate the flow of the vapor through the nozzle, but to keep the opening h² free from any deposit. Moreover, I have found that this form and construction of valve avoids 85 the disagreeable hissing sound so common to lamps of this character.

It may be remarked that in the drawings I have shown a lamp without a hood or inclosing globe, and these may or may not be used, 90 as desired, and may be of any usual or preferred construction.

The operation of the lamp will be readily understood by those skilled in the art from the above description, and it need simply be 95 stated that in starting the lamp the valve c² is opened and the mixed acetylene gas and air ignited at the gas-burner C, and this, as before stated, owing to its arrangement and the extreme heat produced by this mixture 100 of acetylene gas and air, quickly heats the vaporizer, so that almost immediately the valve t can be opened to admit the hydrocarbon to the vaporization-coil A, where it is vaporized, and, passing through the portion 105 A', is projected through the nozzle H and the mixing-chamber tube D into the mixing-chamber E, where the mixing of the vapor and air coming through the intake-tube B is completed, and thence it passes to the burner 110 F, and, being ignited, the flame impinges upon the mantle G, quickly rendering it incandescent and producing the desired illumination. The needle controlling the nozzle can be conveniently adjusted by the thumb-piece l' in connection with the adjusting-nuts i' i² and the ring E².

The construction and arrangement of parts are relatively simple and provide a practically right-line passage-way for the vapor and air through the mixing-chamber tube, tending to avoid the hissing sound, and this, combined with the improved nozzle, practically overcomes this difficulty. Moreover, the arrangement of the acetylene-gas burner in close 125 juxtaposition with the vaporizer above the incandescence enables me to take advantage of the great heating power of acetylene gas and air, and, further, provides such an arrangement of the parts that the initial heat is applied directly to the part desired and in no way interferes with the illuminating qualities of the lamp. Moreover, it will be seen that the mixing-chamber tube is centrally arranged 130

with relation to the cylindrical burner and the mantle or other incandescent material and the vaporization-coil, which latter is in the heat zone of the flame of the burner, avoiding the arrangement of any parts outside of the incandescent material, and thereby preventing shadows, which is an important feature in a single-burner lamp. Further, it will be seen that the vaporization-tube and the Bunsen burner are practically parallel to each other and are both connected to a suitable source of oil and gas supply and that the Bunsen burner is provided with one or more openings so located that jets of flame projecting therethrough will impinge on the vaporization-tube, the burner being closed at one end.

Having thus described in detail the preferred embodiment of my invention and set forth its mode of operation, it will be seen that I am not limited to the precise details of construction and that some of the characteristic features of my invention may be used in combination with other features thereof or with other equivalent constructions and arrangements without departing from the spirit of the invention.

What I claim is—

1. In a vapor-lamp for incandescent lighting, the combination with a vapor-burner, of a vaporizer connected to a source of fuel-supply, a mixed acetylene gas and air burner for preliminarily heating the vaporizer arranged adjacent the latter, and a source of acetylene-gas supply therefor, substantially as described.

2. In a vapor-lamp for incandescent lighting, the combination with a vapor-burner, of a vaporizer in the form of a coil connected to a source of fuel-supply, a mixed acetylene gas and air burner also in the form of a coil for preliminarily heating the vaporizer arranged adjacent the latter, and a source of acetylene-gas supply therefor, substantially as described.

3. In a vapor-lamp for incandescent lighting, the combination with a vapor-burner, of a mixing-chamber connected thereto, incandescent material arranged adjacent the burner, a vaporizer located in the heating zone of the incandescent material, and a mixed acetylene gas and air burner adjacent the vaporizer for producing the initial heating, substantially as described.

4. In a vapor-lamp for incandescent lighting, the combination with a vapor-burner, of a mixing-chamber connected thereto, incandescent material arranged adjacent the burner, a vaporizer, a mixed acetylene gas and air burner for producing the initial heating of the vaporizer, the vaporizer and said burner being located in the heating zone of the incandescent material, and a mixing-chamber tube connecting the vaporizer and mixing-chamber and centrally arranged with relation to the chamber, the incandescent material and vaporizer, substantially as described.

5. In a vapor-lamp for incandescent light-

ing, the combination with a cylindrical vapor-burner, of a mixing-chamber connected thereto, incandescent material arranged in juxtaposition to the cylindrical vapor-burner, a vaporizer, a mixed acetylene gas and air burner for initially heating the vaporizer arranged in juxtaposition thereto, and a mixing-chamber tube centrally arranged with relation to the burner; the incandescent material and the vaporizer, substantially as described.

6. In a vapor-lamp for incandescent lighting, the combination with a cylindrical vapor-burner, of a mixing-chamber connected thereto, incandescent material arranged in juxtaposition to the cylindrical vapor-burner, a mixing-chamber tube centrally arranged with relation to the burner and the incandescent material, an air-intake tube arranged in a right line with said mixing-chamber tube, a vaporization-coil surrounding the air-intake tube, and a mixed acetylene gas and air burner also surrounding the air-intake tube, substantially as described.

7. In a vapor-lamp for incandescent lighting, the combination with a cylindrical vapor-burner, of a mixing-chamber connected thereto, incandescent material arranged in juxtaposition to the cylindrical vapor-burner, a mixing-chamber tube arranged centrally with relation to the burner and incandescent material, an air-intake tube in a right line with said mixing-chamber tube, a vaporization-coil surrounding the air-intake tube and having a portion extending into the same, a nozzle projecting from said portion into the air-intake tube, and a mixed acetylene gas and air burner arranged adjacent the vaporization-coil, substantially as described.

8. In a vapor-lamp for incandescent lighting, the combination with a vapor-burner, of a mixing-chamber connected thereto, incandescent material arranged in juxtaposition to the burner, a mixing-chamber tube, an air-intake tube connected therewith, a vaporization-coil surrounding the air-intake tube and having a portion entering the same and provided with a nozzle projecting into the mixing-chamber tube, a valve for said nozzle extending through the mixing-chamber tube, a plug in the mixing-chamber, a ring connected to the plug, and means for operating the valve, substantially as described.

9. In a vapor-lamp for incandescent lighting, the combination with a vaporizer, of a nozzle, said nozzle comprising a cylinder, a conical plug having its small end projecting into said cylinder, and a needle-valve for said plug, substantially as described.

In testimony whereof I have signed my name to this specification in the presence of two subscribing witnesses.
